UNITED STATES PATENT OFFICE.

JOSEPH BEDARD, OF COLUMBUS, OHIO.

WINDSHIELD-PROTECTOR.

1,392,474.

Specification of Letters Patent.

Patented Oct. 4, 1921.

Application filed August 3, 1920. Serial No. 400,973.

To all whom it may concern:

Be it known that I, JOSEPH BEDARD, a citizen of the United States, residing at Columbus, in the county of Franklin and State of Ohio, have invented a certain new and useful Improvement in Windshield-Protectors, of which the following is a specification.

This invention relates to the class of automobile wind shield protectors of which the patent of the United States issued to me February 4, 1920, No. 1,345,826, affords an example.

Such protectors are designed to protect the shield from snow, rain and glare tending to interfere with a good view of the road by the driver.

The object of the present invention is to provide an improved and simplified form of protector adapted for convenient application and adjustment, the latter both as to size presented and position.

The invention is embodied in the example herein shown and described, the features of novelty being finally claimed.

In the accompanying drawing forming part hereof,

Figure 1 is an end view of a wind shield frame showing one member of my protector frame in side view applied thereto. Fig. 2 is a section on the line II-II Fig. 1 on a larger scale.

Fig. 3 is a side view of a triangular piece of fabric for the corner of the protector frame.

Fig. 4 is a plan view of the top of the protector frame with the fabric broken out.

Fig. 5 is a detail view of one of the forward arms of the protector frame.

As that portion of the protector frame which is connected at one end of the wind shield frame is a symmetrical duplicate of the other a description of one will suffice for both. In the views 6 designates the pro-

tector frame carrying member said carrying member also constituting one of the clamping members for connecting the frame with the wind shield frame 5. The character 6^a designates the other clamping mem-

ber the latter having a threaded stem 6^b to receive a butterfly nut 7 to bind the parts 6 and 6^a upon the wind shield frame. The protector frame includes an upright slotted arm or standard 8 clamped to the part 6 by nuts 9 and 9^a on suitable bolts 10 that pass through the slot of the standard 8 and hori-

zontal slots 6^c so that the arm 8 can be raised and lowered and inclined somewhat forward to change the angle of inclination of the shield proper, if desired. 60

Connected with the upper end of the standard 8 is the rear end of an arm 11 having two longitudinal slots 11^a and 11^b. The connection of the arm 11 with the standard 8 is effected by means of a rod 12, said rod 65 being threaded at its ends, one end being passed through the slot of arm 8 and the lower slot 11^b of the arm and receiving two butterfly nuts like that at 13 between which the arms 8 and 11 are clamped together. The 70 rod 12 extends between the two main parts of the frame as shown and serves to keep those parts properly spaced and in rigid relation to each other. Secured to the outer end and at the inner side of the arm 11 is 75 another slotted arm 14 like the arm 11 (see Fig. 5) except that it has a hole at each end as shown at 14^a and 14^b. The means for securing the arms 11 and 14 together consists of a rod 15 threaded on its opposite 80 ends, such end passing through the lower slots of said arms 11 and 14, said ends provided with butterfly nuts 16 clamping the parts together. The outer ends of the arms 14 are braced by a rod 17 threaded at its ends 85 and provided with suitable butterfly nuts 18 to clamp said arms and hold the several parts in fixed relation to each other.

The top of the wind shield is braced by a pair of slotted arms 20 and 21 clamped 90 at their meeting ends by a bolt and nut, as seen at 22, the other ends being clamped respectively to the frame carrying member 6 by nut 9 and to the arms 11 and 14 by nut 16. 95

The upper part of the frame is thus composed of a rear portion and a forward portion, the forward portion comprising the side arms 14 with bars 15 and 17 slidable in the slots 11^b of the rear portion. 100

A bolt 25, nut 26 and spacing washer 27 between the arms 11 and 14 keeps those arms in proper position to permit the easy sliding of the forward part in the rear part when the nuts 16 and 26 are loosened. 105

A suitable piece of opaque flexible fabric 28 is stretched and secured between the arms 11, the said fabric being passed through the slots at 11^a and under the upper bars of said arm and stitched. A piece of similar fabric 29 is likewise secured between the upper bars of the arms 14. To hold the fabrics 110

closed together in adjusted relation they can be provided with ordinary snap fasteners as at 28^a and 29^a.

In Fig. 3 I have shown a triangular piece 5 of fabric 30 that can be employed to cover the triangular opening included by the arms 8, 11 and the bracing arms, said triangular piece being provided with suitable holes 31 placed to be buttoned upon the 10 butterfly nuts even if the angle of the frame be changed.

It will be observed that my protector frame is adjustable to suit any conditions it may be desired to meet. If not needed 15 on the vehicle it can be taken down and reduced to compact form.

The forms of the parts can be changed without departing from the gist of the invention as claimed.

20 What I claim is:

1. A wind shield protector including, in combination, suitable standards, a top for connection with said standards comprising a rear part and a forward part, the rear 25 part including a pair of longitudinally slotted side bars, a threaded rod and clamping nuts thereon connecting said side bars to said standards, the forward part of said top including side bars each having a lon- 30 gitudinal slot and a hole in the end thereof beyond said slot, clamping means connecting the forward ends of the rear side bars with the rear ends of the forward side bars at their slots adapted to permit the sliding 35 of the forward side bars with relation to

the rear side bars, and means connecting the forward side bars at the rear holes thereof at the slots of the rear bars adapted to hold the forward and rear bars in parallel relation to each other, a rod 40 connecting the forward ends of the forward side bars and separate coverings secured to and extending between said rear and forward side bars respectively.

2. A wind shield protector, including, in 45 combination, suitable standards and slotted brace members, a top for connection with said standards comprising a rear part and a forward part, the rear part including a pair of longitudinally slotted side bars, a 50 threaded rod and clamping nuts thereon connecting said side bars to said standards, the forward part of said top including side bars each having a longitudinal slot and a hole in the end thereof beyond said slot, 55 clamping means connecting the forward ends of the rear side bars with the rear ends of the forward side bars and the brace members at their slots adapted to permit the sliding of the forward side bars with 60 relation to the rear side bars, and clamping means connecting the forward side bars at the hole thereof and at the slots of the rear bars adapted to hold the forward and rear bars in parallel relation to each other, a rod 65 connecting the forward ends of the forward side bars, and separate coverings secured to and extending between said rear and forward side bars respectively.

JOSEPH BEDARD.
